Application April 19, 1939, Serial No. 84,382

To all whom it may concern:

Be it known that I, Harold E. Nock, a citizen of the United States, residing at Newburyport, in the county of Essex and Commonwealth of Massachusetts, have invented a new, original, and ornamental Design for a Spoon or Analogous Article, of which the following is a specification, reference being had to the accompanying drawing, forming a part thereof.

In the accompanying drawing, Figure 1 is a front elevational view of a spoon showing my new design, and Fig. 2 is a sectional view of the handle taken on the line 2—2 of Fig. 1.

The dominant feature of my design is shown in the drawing by the full lines delineating the ornamental handle, the dotted lines of Fig. 1 indicating the conventional bowl of a spoon.

My design is delineated as embodied in the handle of a spoon but the design may also be embodied in or applied to other handles of like nature.

I claim:

The ornamental design for a spoon or analogous article, substantially as shown and described.
